J. A. DAILEY

FURNITURE ATTACHMENT

Filed May 24, 1922

UNITED STATES PATENT OFFICE.

JAMES A. DAILEY, OF MILWAUKEE, WISCONSIN.

FURNITURE ATTACHMENT.

Application filed May 24, 1922. Serial No. 563,363.

To all whom it may concern:

Be it known that I, JAMES A. DAILEY, a citizen of the United States, residing at Milwaukee, in the county of Milwaukee and

5 State of Wisconsin, have invented a certain new and useful Improvement in Furniture Attachments, of which the following is a full, clear, concise, and exact description, reference being had to the accompanying 10 drawings, forming a part of this specification.

This invention relates to furniture attachments and, though capable of use in other relations, has reference primarily to ironing board attachments for kitchen cabinets.

One object of the present invention is the provision of an adjustable support for mounting a board on a cabinet in such manner as to permit the ready removal of the 20 board from a convenient working position above the table of the cabinet to an inconspicuous position against or adjacent one end thereof.

Another object is the provision of an ironing board attachment which may be applied to any standard cabinet without modification thereof and such that the board, when not in use, may be removed to an inconspicuous position without necessitating any appreciable additional space beside the cabinet.

Other objects and advantages will later appear.

Two embodiments of the invention are illustrated in the accompanying drawings, in 35 which:

Figure 1 is a perspective view of a kitchen cabinet provided with an ironing board attachment constructed in accordance with the present invention.

40 Figure 2 is a fragmentary end elevation of a cabinet showing the ironing board attachment of Figure 1 applied thereto.

Figure 3 is a detail sectional view on a somewhat larger scale, taken on the line 45 3-3 of Figure 2.

Figure 4 is a view similar to Figure 2 showing another form of ironing board attachment.

50 Figure 5 is a detail sectional view on a somewhat larger scale, taken on the line 5-5 of Figure 4.

The cabinet of Figure 1 is of a well known construction and includes the usual top portion 10 supported by a base portion 55 11. The base portion is somewhat deeper than the top portion to form the usual ledge

12. The cabinet is also provided with the usual slidable table board 13 resting upon the ledge and confined between the curved sheet metal guide plates 14.

60 The ironing board 15, which may be of any appropriate construction, is positioned, when in use, above the table 13, as shown in full lines in Figure 1. It is so mounted, however, that when not in use, it may be 65 readily removed to an upright position against the end wall 16 of the cabinet, substantially as shown in dotted lines in this figure. In this latter position, it cannot in any manner interfere with the ordinary 70 uses to which the cabinet is put nor detract materially from the general appearance of the cabinet. Furthermore, it occupies very little space in addition to that ordinarily required for the cabinet.

75 In this instance, the board is connected with the cabinet by means of an adjustable support of such construction as to permit the board to be swung from its horizontal working position to an upright or substan-

80 tially vertical position and then shifted edgewise toward the rear of the cabinet. An adjustable support of this character is illustrated in Figures 2 and 3. The support therein shown comprises a rigid bar 17 of 85 squared section, secured in horizontal position upon the end wall 16 of the cabinet by any appropriate means, such as the bracket plates 18. Bar 17 is preferably mounted below the level of the ledge 12. A supporting carriage is slidably mounted upon bar 17. This carriage includes a pair of upright bracket arms 19 provided with squared openings 20, slidably fitted to the bar 17 and rigidly connected by tie rods 21 and 22. 90 Tie rod 22 forms a pivoted support for a pair of bracket plates 23, fixed preferably to the bottom of the ironing board 15.

95 It will be noted that the arms 19 extend preferably well above the level of the table board 13 in order that the ironing board may be positioned at the most convenient height for use. When so positioned, it is essential, or at least highly desirable, that some appropriate means, such as a leg 24, 100 be provided for supporting the free end of the ironing board. In the present instance, this leg is hinged to the under side of the ironing board in order that it may be folded back to economize space when the board is 110 not in use. It will be further noted that the bar 17 and bracket arms 19 are com-

pactly arranged as close as possible to the end wall 16 of the cabinet. In order to clear the projecting guide plates 14, these arms 19 may be suitably curved as shown.

- 5 Thus it will be seen that a simple adjustable support has been provided by which the board may be swung about the rod 22 from the full line position of Figure 1 to an upright position and then shifted rearwardly along the bar 17 to the dotted line position. When in this latter position, neither the board nor its support will in any way interfere with the uses to which the cabinet may be put nor detract from the neat 10 appearance thereof. Furthermore, the adjustment of the board to and from working position requires very little space, in addition to the space normally occupied by the cabinet.
- 15 Another form of adjustable support for the ironing board is illustrated in Figures 4 and 5. This support is similar in many respects to that above described, except that the bar 17' and the openings 20' in the 20 bracket arms 19' are round instead of square. In this instance, each bracket arm is provided with a keyway 25 for receiving a key 26 secured to the bar 17'. The key 26, as shown in Figure 4, extends only along the 25 forward end of the bar. Thus it insures an upright position of the arms 19' when the ironing board is in working position, but when the board and its supporting carriage has been shifted to the rear, the key 26 no 30 longer engages the keyways 25 and the arms 19' are permitted to swing about the bar 17' to the dotted line position of Figure 5. This permits the ironing board to assume a 35 lower position adjacent the end wall of the cabinet when not in use. By this construction, a longer board may be used without danger of its projecting above the cabinet 40 when in closed position.

Various changes may be made in the invention above described without departing from or sacrificing any of the advantages of the invention, as defined in the appended claims.

I claim:

- 50 1. An attachment for kitchen cabinets, including an ironing board, a bar for mounting in fixed horizontal position adjacent the end of the cabinet, a carriage mounted on

said bar for movement longitudinally thereof forwardly and rearwardly of the cabinet, and means for pivotally connecting the board with the carriage.

2. The combination with a kitchen cabinet having a table portion and a cupboard portion extending above said table portion of an ironing board attachment therefor comprising a board, and connections between said board and cabinet permitting an adjustment of said board from a substantially horizontal position over said table portion to a substantially vertical position adjacent the end wall of said cupboard portion.

3. An attachment for kitchen cabinets, including a board, a supporting bar for attachment to the cabinet, means including a plurality of bracket arms slidably mounted on said bar, and a plurality of bracket plates for connection with the board and pivotally connected with said bracket arms.

4. An adjustable support for mounting a board upon a cabinet including a member for connection with the cabinet, a member for connection with the board, a pivotal connection between said members to permit movement of said board from horizontal position to a substantially vertical position parallel with the end of the cabinet, and a sliding connection between said members to permit movement of the board in a direction parallel with the end of the cabinet.

5. The combination with a kitchen cabinet having a table portion and an end wall extending thereabove of a horizontal bar mounted on said end wall below the level of said table, a board, and connections between said board and bar projectable above said table portion and permitting adjustment of said board from substantially horizontal position over said table portion to substantially vertical position adjacent said end wall.

6. An attachment of the character described comprising a bar, means including a bracket arm slidably mounted on said bar, means pivotally connected with said bracket arm for attachment with a board, and means for preventing swinging movement of said arm about said bar when said arm is in a certain position on said bar.

In witness whereof, I hereunto subscribe my name this 22nd day of May, 1922.

JAMES A. DAILEY.
